UNITED STATES PATENT OFFICE.

ISAAC L. RHEUTAN, OF RICHMOND, VIRGINIA, ASSIGNOR TO UNION ENVELOPE COMPANY, OF RICHMOND, VIRGINIA, A CORPORATION OF VIRGINIA.

ENVELOP.

1,136,614.

Specification of Letters Patent. Patented Apr. 20, 1915.

Application filed October 21, 1914. Serial No. 867,819.

To all whom it may concern:

Be it known that I, ISAAC L. RHEUTAN, a citizen of the United States, residing at Richmond, in the county of Henrico and 5 State of Virginia, have invented certain new and useful Improvements in Envelops; and I do hereby declare the following to be a full, clear, and exact description of the invention, such as will enable others skilled 10 in the art to which it appertains to make and use the same.

My invention relates to improvements in envelopes and more particularly to the twin or duplex type, and while designed especially for church collections, it may be employed for any use to which it may be adapted.

One of the objects of my invention is to provide an envelop of this type, which may 20 be made up on the ordinary machine in less time than those envelopes heretofore in use.

Another object of my invention is to form the blank in such manner that the surface upon which the identification number is 25 stamped, will be smooth and without seam.

A further object is to provide an envelop which may be sealed, without having the user's tongue come in contact with the adhesive.

30 To the above mentioned ends, the invention primarily contemplates an envelop of the duplex type, embodying means in connection with the back flap which allow said back flap to be folded in making up the envelop before the machine folders for the side flaps have been withdrawn.

The essential features of the invention involved in the novel form of blank and arrangement of the adhesive, is susceptible to 0 structural modification, without departing from the scope of my invention, but a preferred embodiment thereof is described in the following specification, illustrated in the accompanying drawings, and more particularly pointed out in the appended claims.

45 In the drawings, Figure 1 is a plan view of my improved envelop blank. Fig. 2 is a similar view showing the side flaps folded. Fig. 3 is a plan view from the rear showing the back flap folded upon the side flaps. Fig. 4 is a plan view showing the completed envelop.

The numeral 1 designates the main body portion of my improved envelop, which is 50 rectangular in shape, and is provided on its

lateral edges with side flaps 2, on its lower edge with a back flap 3, and on its upper edge with a sealing flap 4. These flaps are folded along the lines 5, 6 and 7 respectively, to form the complete envelop. The side 60 flaps 2 are provided with extensions 8 for a purpose hereinafter described and in making up the envelop they are folded over on the lines 5 and have their then visible surface provided with an adhesive 9. The back 65 flap 3 corresponds approximately in form and dimensions to the body portion 1, upon which it is superposed when folded to provide a large unbroken surface upon the rear of the envelop for the purpose of printing 70 informative data. Adhesive 10 is applied upon the back flap 3 and upon the body portion intermediate their lateral edges and when the envelop is folded this forms the two pockets for the twin envelop. By providing the gum 10 upon both the body portion and the back flap 3, a decided improvement is gained from a mechanical standpoint. For example, an adhesive in order 75 to cause two surfaces of paper to adhere or unite, must soften and penetrate the fibers of the paper, or the gum will crystallize between the two surfaces when they are brought together, and there will not be a permanent adhesion after the gum is thoroughly dry. This defect often causes the 80 contents of the envelop to break through the gummed edge after the envelop has been torn apart to form two envelopes. By employing a double strip of gum as shown in 85 the drawings, both of the surfaces when brought together are gummed and penetrated by moisture and consequently the adhesion is better and more complete than when a moist surface and a dry one are 90 brought together, as in the envelopes heretofore known. A score line 11 is provided across the face of the completed envelop intermediate its ends for the purpose of separating the sealed pockets. Notches or cut 95 out portions 12 are provided in the corners of the back flap, and similar notches or recesses 13 are provided in the corners of the sealing flap 4, and are adapted to register with the notches 12 when the envelop is completely folded.

The particular advantages gained in providing the seal and back flaps with registering notches are, first, that a number designated 14 on the drawings, which is placed on 100

the envelop for the purpose of identification, may be printed on a smooth surface consisting of only two thicknesses of paper, void of seams, thereby assuring the printer a surface that will always permit a clear and distinct impression to be made. Second. The side flaps may be folded and held down by the side folders used in making the envelop, while the back flap is being brought down 10 upon them by the back folder.

The method of folding an envelop from a died out blank is as follows: The blank is picked up from the top of a pile of blanks, which are placed on the elevator of the folding 15 machine by the pickers, which have been supplied with a coat of gum, and placed on a conveyer which carries them to the folding box. This folding box is of a size approximately the size of the folded envelop. When 20 the envelop blank has been brought directly over the folding box, a plunger forces the blank down through the folding box to the bed of the machine, thereby creasing the blank on the four edges of the body of the 25 envelop and leaving all four flaps standing in a perpendicular position. Attached to the bed of the machine of each of the four sides of the folding box are the folders, each hinged so that they oscillate through 30 the arc of a circle. The folders are employed in laying down the flaps of the envelop, folding them from their standing position onto the body of the envelop. All 35 of the folders cannot be operated simultaneously but operate in the following order, viz:—First, the two side folders are actuated contemporaneously. The back folder is then operated and finally the folder for the sealing flap.

40 In making envelops as heretofore constructed, it was necessary to raise the side folders, after they had operated, before the back folder could fold the back flap. To do this it was essential to employ side folders 45 which have a rapid oscillating motion, that is, the side folders must be brought down and returned to normal position before the back folder is started down. In doing this the blank is left without any control to hold 50 it in position on the bed of the machine and it frequently moves from its proper position before the folders perform their functions. Again, the returning of these side folders before the back folder operates, diminishes 55 the speed of the machine very materially, and its daily product is accordingly decreased. In making my improved envelop, side folders can be used which have projections on them that are adapted to engage 60 the extensions 8 to fold the side flaps and owing to the back and seal flaps being notched, as heretofore described, the back and seal flaps can be folded before the side folders are raised. In other words, all of 65 the folders can be operated at very nearly

the same time, the two side folders being timed just in advance of the back folder and the back folder just in advance of the sealing flap folder.

The adhesive for sealing the top or sealing flap 4 is provided at 15 upon the back flap 3 and an envelop manufactured in this manner in the twin style is most desirable for the reason that when the gum is applied, there is danger, especially in damp 70 weather, of the gum not drying on the seal flap before the envelopes are boxed up, causing the flap to adhere to the body of the envelop. It is also a fact, that the adhesive 75 10 which divides the envelop into two compartments does not dry thoroughly for a long period after the envelopes are made, and when the envelopes are boxed up, the moisture which emanates from the dividing line of adhesive, causes the top flap when 80 gum is provided thereon, to stick at this point, thereby making the envelop unfit for use on an automatic printing machine. By applying the gum to the body of the envelop this defect will be eliminated. A further advantage in applying the adhesive 85 upon the back flap is that the seal flap always lies straight and does not curl after 90 the envelop is made. It is a well known fact that when gum is applied to paper, 95 the paper immediately curls on account of the moisture in the gum. Where the seal flap is short, as is necessary in a duplex envelop, it is difficult to control the position 100 of the seal flap while the envelop is drying 105 in the drying chain of the envelop machine. Omitting the gum from the seal flap and placing it on the back flap 3 allows the envelop machine to increase its production. Also in feeding this type of envelop into 110 automatic printing presses, the blades or fingers which do the feeding, pass under the sealing flap between the flap and the body 115 of the envelop, to feed the envelopes one at a time to the grippers. If the sealing flaps 110 are stuck down, as often happens, the feed misses and as the dating and numbering mechanism of the printing press is designed for continuous feed, the printing is dis- 120 arranged on a set of fifty-two envelopes, and the machine has to be stopped, and the dates and numbers reset, thereby causing great annoyance and loss of material. By my improvement the drying can be better taken care of and the liability of "adhering flaps" 125 is decreased to a minimum and also the user or sealer of the envelopes does not have to bring his tongue into contact with the adhesive, he merely moistening the seal flap 4 and pressing it into contact with the ad- 130hesive 15. It is also obvious that by placing the gum upon the back flap, the moistening of the sealing flap does not remove any of the gum, thereby weakening the closure.

It will be seen and appreciated from the

foregoing, that I have devised an improved envelop, which has particular merits for the purpose intended and one which may be made at greater speed and at less expense than those heretofore known.

What I claim and desire to secure by Letters Patent is:—

1. An envelop comprising a body portion provided with side flaps, a back and a sealing flap, the side flaps being folded inwardly upon the body and being provided with an adhesive, said back flap being of approximately the same dimensions as the body and being superposed upon the side flaps, and registering notches provided in said back and sealing flaps adapted to register over said side flaps when all of said flaps are folded, whereby the folders for the side flaps, used in manufacturing an envelop, may remain depressed while the back and sealing flaps are being folded.
2. A twin envelop comprising a body portion provided with side flaps, a back and a sealing flap, the side flaps being folded inward upon the body and being provided with an adhesive, and the back flap being provided intermediate its ends with a line of adhesive which divides the envelop into two pockets when the back flap is superposed upon the side flaps, said back flap being of approximately the same dimensions

as the body portion and being provided at its corners with notches, and the sealing flap being superposed upon the said back flap and having its corners notched to correspond with the notched portions of the back flap whereby said notched portions will register over the side flaps in the complete envelop.

3. An envelop comprising a body portion provided with side flaps, a back and a sealing flap, the side flaps being folded inwardly upon the body and being provided with an adhesive, said back flap being of approximately the same dimensions as the body and being superposed upon the side flaps, and registering notches provided in said back and sealing flaps, whereby the folders for the side flaps, used in manufacturing an envelop, may remain depressed while the back and sealing flaps are being folded, and an adhesive provided upon the upper outer surface of said back flap for engagement with the sealing flap when the envelop is closed.

In testimony whereof I affix my signature, in the presence of two witnesses.

ISAAC L. RHEUTAN.
